UNITED STATES PATENT OFFICE.

GEORGE E. HENRY, OF BELLMORE, NEW YORK, ASSIGNOR TO THE J. G. BRILL COMPANY, OF PHILADELPHIA, PENNSYLVANIA, A CORPORATION OF PENNSYLVANIA.

CAR-SEAT.

1,364,756.

Specification of Letters Patent.

Patented Jan. 4, 1921.

Application filed December 10, 1919. Serial No. 343,694.

To all whom it may concern:

Be it known that I, GEORGE E. HENRY, a citizen of the Republic of Switzerland, (the said HENRY having declared his intention of becoming a citizen of the United States,) and a resident of Bellmore, Long Island, Nassau county, New York, have invented certain Improvements in Car-Seats, of which the following is a specification.

10 One object of my invention is to provide a seat at each end of a car, which can be used by the motorman, when necessary, and when not used by the motorman can be occupied by passengers.

15 A further object of the invention is to design the car seat so that the seat section can be raised when the seat is to be used by the motorman and lowered when the back is shifted and it is to be used by passengers.

20 In the accompanying drawings:

Figure 1 is an end view of a car seat illustrating my invention;

Fig. 2 is a front view, showing the back of the seat section broken away;

25 Fig. 3 is an enlarged sectional view, showing the seat section in the lower position;

Fig. 4 is a similar view, showing the seat section raised;

30 Fig. 5 is a sectional plan view on the line 5—5, Fig. 4;

Fig. 6 is a sectional view on the line 6—6, Fig. 3;

Fig. 7 is a perspective view illustrating a detail of the invention; and

35 Fig. 8 is a diagrammatic plan view of a car showing the location of the seats.

1 is a portion of the fixed frame of a car, on which is a bracket 2, supporting one end of the car seat structure. 3 is a pedestal 40 supporting the other end of the seat structure. This pedestal has an end section 4 enclosing the mechanism for raising and lowering the car seat. 5, 5 are two shafts, which extend from one side frame 4 to the other side frame 6, and have their bearings in said frames. These two shafts are attached to two links 7, 7 connected to pivots 8 on a back section 9. This back section can be turned from one side of the seat section to

the other in the ordinary manner, when it 50 is desired to reverse the seat.

10 is the seat section. Attached to this seat section are two sliding members 11, one at each end of the seat section. These members are adapted to guides 12 in the structures 4 and 6 and a cross bar 13 extends from one side member 14 of the structure 11 to the other, being in position to be acted upon by cams 15 rigidly secured to the two shafts 5 at each end of the seat structure. 60 These cams are so shaped that when the back section is moved to the position shown in Fig. 1, the seat section is raised and can be used by the motorman, the back section 9 of the seat preventing its use by a passenger. When the motorman drives the car from the opposite end, then the seat, heretofore occupied by him, is adjusted by moving the back 9 and lowering the seat section, as shown in Fig. 3, to the normal level 70 of a car seat, so that it can be used with ease by passengers.

The structures 11 are rigidly secured to the under side of the seat section 10 by bolts, or other fastenings, and the vertical 75 members 14 are beveled at each end so as to fit the slideway in the fixed portion of the seat structure, making the seat rigid when raised or lowered.

Thus, it will be seen by the above construction that a car can be provided with seats at each end, thereby increasing the seating capacity, as well as the comfort of the passengers.

I claim:

1. The combination in a car seat, of a fixed body portion having slideways at each end; a seat section having structures secured to its ends and adapted to slide in the ways in the body portion; a back section capable 90 of being moved from one side of the seat to the other; and means, actuated by the back, for raising the seat in its side guides when the back is shifted to one side and lowered when the back is shifted to the opposite 95 side.

2. The combination in a car seat, of two parallel shafts mounted in bearings in the

fixed portion; a slideway at each end of the fixed portion, said slideway having beveled sides; a seat section having depending structures secured thereto and shaped to conform 5 to the slideways, each structure having a cross bar; two cams on each shaft adapted to bear upon the cross bars of the seat structures; a seat back; links connecting the seat

back to the shafts, said back being capable of being moved to either side of the seat 10 structure, the parts being so arranged that when the back is moved to one side the seat will be raised and, when moved to the opposite side, the seat will be lowered.

GEORGE E. HENRY.
